UNITED STATES PATENT OFFICE.

EGON EICHWALD, OF HAMBURG, GERMANY.

PROCESS FOR PURIFYING OILS AND THE LIKE.

No Drawing.

Application filed June 2, 1923. Serial No. 643,082.

To all whom it may concern:

Be it known that I, EGON EICHWALD, residing at Hamburg, Germany, have invented certain new and useful Improvements in and Relating to Processes for Purifying Oils and the like, of which the following is a specification.

Various means and processes have been proposed for purifying oils and oil-like products for the separation of aromatic substances from the other components of mineral and tar oils of different kinds and for the extraction of paraffins from the tar oil distillates. These methods have either proved entirely unsuccessful, when applied on a large scale, or they can only be carried out with considerable trouble and at great expense. The latter also applies in the case of the two processes, which are based on the use of acetone or of liquid sulphurous acid as solvents for certain components. In both processes the work must be carried out at fairly low temperatures. Acetone dissolves, besides the aromatic compounds, a considerable portion of the hydro-aromatic naphthalene-like oils, for instance hexahydro-toluene, resulting in losses. Liquid sulphurous acid must be used in fairly large quantities, the amount being, say, from one to two parts for every part of raw oil, its use and recovery entailing costly apparatus and causing difficulties in working. Hence, there is need for a simple purifying process of this kind, which can be carried out easily and economically. This is provided for by the process according to the present application.

Furfurol is produced in large quantities as a by-product in the hydrolysis of cellulose and some suitable way of making use of it has been sought. In the experiments carried out with this object it was found, that furfurol and its derivatives are very suitable for readily obtaining from aliphatic and hydro-aromatic hydro-carbons and their mixtures, phenols, alcohols, asphalts, naphthalene acids and sulphur-containing compounds of this kind, tar-forming substances and the like. The term "furfurol derivatives" means those derivatives of furfurol which are present as admixtures in furfurol obtained from cellulose, and which perhaps in the future may be obtained in still greater quantities than they are to-day. This led to the process according to the present application, which is described below in connection with three examples.

(1) Four parts by weight of Pennsylvanian petroleum having a viscosity of 2.1° Engler at 50° are intimately mixed with one part by weight of furfurol, the mixture being allowed to stand. After a short time the layer of furfurol will have become deposited at the bottom. The colour of this layer is dark owing to the substances which have separated off. About 5% substances consisting substantially of aromatic oils have been taken up by the furfurol. In that part which is not released there will be about 4% of furfurol, which is recovered by evaporation in vacuo at 80-90°. After the furfurol has been distilled off the aromatic oils of the solution may be used for all purposes for which they can otherwise be used.

(2) One part by weight of low temperature tar oil from lignite having a boiling point of 275-300° is treated with one part by weight of furfurol, as in the first example. About 40% aromatic oils will go into solution. Lignite-low temperature tar oils contain 40% or more of aromatic substances, which can be extracted with furfurol or furfurol derivatives. The aliphatic oils, which are separated off, are light coloured and do not become dark later.

(3) Four parts by weight of a Mexican raw oil having a sulphur content of 2.1% are treated with one part by weight of furfurol, as in example (1). 7% will go into solution. The purified oil will only contain 0.3% of sulphur.

The amount of furfurol or of the furfurol derivatives, which are added to the oil or oil-like product to be purified, is determined by preliminary experiments, the treatment of the oil with furfurol or the derivatives thereof being repeated if necessary. Generally good results are obtained at ordinary temperatures. The temperature may, however, be adapted to the particular oil to be purified for assisting the separation, and the separation of the components of the oil may be effected in some cases at a reduced or increased temperature by means of furfurol.

I claim:

1. A process for purifying hydrocarbon-like oils or their admixtures, with organic solvents, more particularly for separating the aromatic oil-like substances contained therein from aliphatic and hydro-aromatic oil-like compounds, consisting in adding a quantity of a substance containing furfurol to the oils or their admixtures and inti-

mately mixing it therewith, allowing the mixture to stand, and separating the layer of the substances containing furfural from the remaining portion, as and for the purpose set forth.

2. A process for purifying hydro-carbon oils or their admixtures with organic solvents, consisting in adding a quantity of

furfural to the oils or their admixtures and intimately mixing the furfural therewith, allowing the mixture to stand, and then separating the layer of furfural from the remainder of the mixture.

In testimony whereof I affix my signature.

EGON EICHWALD.
